UNITED STATES PATENT OFFICE.

GEORGE HRIB, OF SIMPSON, WEST VIRGINIA.

GEAR BOX AND DRIVE FOR AEROPLANE-PROPELLERS.

1,377,483.

Specification of Letters Patent.

Patented May 10, 1921.

Application filed February 2, 1921. Serial No. 441,872.

To all whom it may concern:

Be it known that I, GEORGE HRIB, a citizen of Czechoslovakia, residing at Simpson, in the county of Taylor and State of West Virginia, have invented certain new and useful Improvements in Gear Boxes and Drives for Aeroplane-Propellers, of which the following is a specification.

This invention relates to certain new and useful improvements in a driving gear for a horizontal propeller for aeroplanes with a box for containing the gearing and has particular reference to the particular disposition of the gears in a train for obtaining the maximum speed of rotation of the propelling blades from the power employed.

A further object of the invention is to provide a gear drive for a horizontally disposed propeller for an aeroplane with a lever latch device adapted to be moved to a position for engagement with the blades to hold the propeller stationary when the same is out of use.

With the above and other objects in view, the present invention consists in the novel combination and arrangement of parts hereinafter more fully described and shown in the accompanying drawings, in which like reference characters indicate corresponding parts throughout the several views.

In the drawings,

Figure 1 is a fragmentary side elevational view, partly in section of an aeroplane constructed in accordance with the present invention with the lever latch device for holding the horizontal propeller stationary moved to its inoperative position as indicated by dotted lines.

Fig. 2 is a top plan view of the construction shown in Fig. 1.

Fig. 3 is a fragmentary elevational view partly in section showing the gear casing, train of gearing therein and the connections between the train of gearing and the vertical shaft supporting the horizontal propeller.

Fig. 4 is a detail sectional view taken on line IV-IV of Fig. 3.

Fig. 5 is a detail sectional view on line V-V of Fig. 4.

Fig. 6 is a horizontal sectional view taken

through the supporting stand for the horizontal propeller shaft showing the bracket mounting for the lever device to hold the horizontal propeller stationary, and

Fig. 7 is a horizontal sectional view similar to Fig. 6 showing the sliding guide for the operating end of the lever device.

Describing the invention in detail, and in particular reference to Figs. 1 and 2, there is shown a fuselage body 1 provided with a forward deck portion 2 upon which a motor 3 is mounted with the propeller shaft 4 thereof supporting a forward propeller 5.

A horizontal elevating propeller is carried by the fuselage 1 and driven by a gearing train connection with the motor 3, the horizontal propeller being supported on a pair of vertical standards 6 and 7 having anchoring feet 8 secured to the fuselage 1 with the upper end thereof connected by a strap clamp 9. A vertical shaft 10 is journaled in grooved bearings 11 in the standard sections 6 and 7 and carries a horizontal propeller 12 at the upper end thereof, the grooved bearings 11 being enlarged adjacent their lower ends as at 13 to accommodate the worm 14 carried by the shaft 10 while the standard section 7 has a side opening slot 15 shown more clearly in Figs. 3 to 5 communicating with the worm 14 for purposes presently to appear.

A train of gearing communicates motion from the motor 3 to the worm 14 of the shaft 10, the same being located within a box casing 16 having a lateral inclosing portion 17 for the adjacent end of the power shaft 4. The power shaft 4 and driven shaft 18 of the gearing train are mounted in spaced bearings 19 with an intermediate clutch device 20 shifted by the lever 21 pivoted to the box extension 17 as shown in Figs. 1 and 3. A shaft 22 is journaled in the casing 16 and has fixed to one end thereof adjacent the vertical standard, a worm wheel 23 while the other end of the shaft 22 carries a gear wheel 24 that is in constant mesh with the gear wheel 25 upon the end of the driven shaft 18 that extends into the box casing 16. A second shaft 26 is journaled in the side walls of the box casing 16 at right angles to the shaft 22

and beneath the same, the shaft 26 carrying a small worm 27 in mesh with the large worm 23 upon the shaft 22 while a larger worm wheel 28 is fixed to the shaft 26 and extends through the side opening 15 in the standard section 7 in engagement with the worm 14 upon the shaft 10.

The forward propulsion of the aeroplane is effected by the forward propeller 5 while 10 the elevating movement of the plane is effected by the horizontal propeller 12. By shifting the clutch device 20, the train of gearing is thrown into and out of engagement with the power shaft 4 and the gear- 15 ing train being connected with the vertical shaft 10 of the worm 14 and worm wheel 28, the shaft 10 and propeller 12 carried thereby are revolved.

When the train of gearing is disconnected 20 from the engine shaft 4, the horizontal propeller 12 is maintained against rotative movement by the lever 29 pivoted to the bracket 30 adjacent the upper end of the standard section 6 with the upper end of 25 the lever being angularly directed and forked as at 31 for inclosing one of the blades of the propeller 12 as shown in Fig. 2. The lower end of the lever 29 extends through a slotted guide 32 carried by the 30 lower end of the standard section 6 with the latch device 33 upon the lower end of the lever engaging in notches upon the slotted guide for holding the propeller control lever in its adjusted positions. When the 35 vertical shaft 10 is disconnected from the power shaft 4, the lever 29 holds the same against rotation so that the propeller will not effect the forward travel of the machine. With the ratio of gearing herein 40 illustrated, the maximum speed of rotation may be accomplished for the propeller blade 12 so that the machine will be caused to rise at a great rate of speed.

While there is herein shown and described 45 what is believed to be the preferred embodiment of the invention, it is nevertheless to be understood that minor changes may be made in the form, combination and arrangement of parts herein set forth without departing from the spirit and scope of the invention as claimed.

What is claimed as new is:

1. A propeller shaft drive for aeroplanes comprising a vertical standard, a shaft 55 journaled in said standard, a propeller upon the upper end of said shaft, a worm fixed to said shaft within the standard, said standard having a side opening therein exposing the worm and a train of gearing including 60 a worm wheel extending into said opening for engagement with said worm.

2. A propeller shaft drive for aeroplanes comprising a vertical standard, a shaft journaled in said standard, a propeller upon 65 the upper end of said shaft, a worm fixed to

said shaft within the standard, said standard having a side opening therein exposing the worm, a gear casing supported adjacent said standard, a pair of crossed shafts journaled in said casing, a pair of worm wheels 70 fixed to one of said shafts with one of said wheels extending into the standard opening for engagement with the worm, a worm fixed to the other shaft in engagement with one of the worms upon the first named 75 shaft, a gear carried by the last named shaft and a driven shaft carrying a gear in mesh with the aforesaid gear.

3. A propeller shaft drive for aeroplanes comprising a vertical standard, a shaft journaled in said standard, a propeller upon the upper end of said shaft, a worm fixed to said shaft within the standard, said standard having a side opening therein exposing the worm, a gear casing 80 supported adjacent said standard, a pair of crossed shafts journaled in said casing, a pair of worm wheels fixed to one of said shafts with one of said wheels extending into the standard opening for engagement with the worm, a worm fixed to the other shaft in engagement with one of the worms upon the first named shaft, a gear carried by the last named shaft, a driven shaft carrying a gear in mesh with the aforesaid gear, 85 a motor, and clutch devices connecting the shaft of the motor to the driven shaft.

4. A propeller shaft drive for aeroplanes comprising a vertical standard, a shaft journaled in said standard, a propeller upon the upper end of said shaft, a worm fixed to said shaft within the standard, said standard having a side opening therein exposing the worm, a gear casing supported adjacent 100 said standard, a pair of crossed shafts journaled in said casing, a pair of worm wheels fixed to one of said shafts with one of said wheels extending into the standard opening for engagement with the worm, a worm fixed to the other shaft in engagement with one of the worms upon the first named shaft, a gear carried by the last named shaft, a driven shaft carrying a gear in mesh with the aforesaid gear, 105 a motor, and clutch devices connecting the shaft of the motor to the driven shaft.

5. A propeller shaft drive for aeroplanes comprising a vertical standard, a shaft journaled in said standard, a propeller upon the upper end of said shaft, a worm fixed to said shaft within the standard, said standard having a side opening therein exposing 110 the worm, a gear casing supported adjacent said standard, a pair of crossed shafts journaled in said casing, a pair of worm wheels fixed to one of said shafts with one of said wheels extending into the standard opening for engagement with the worm, a worm fixed to the other shaft in engagement with one of the worms upon the first named shaft, a gear carried by the last named shaft, a driven shaft carrying a gear in mesh with the aforesaid gear, 115 and a lever pivoted to said standard adapted to be moved to engaging position with said propeller for holding the same against rotation.

6. A propeller shaft drive for aeroplanes comprising a vertical standard, a shaft journaled in said standard, a propeller upon the upper end of said shaft, a worm fixed to said shaft within the standard, said standard having a side opening therein exposing 120 the worm, a gear casing supported adjacent said standard, a pair of crossed shafts journaled in said casing, a pair of worm wheels fixed to one of said shafts with one of said wheels extending into the standard opening 125 for engagement with the worm, a worm fixed to the other shaft in engagement with one of the worms upon the first named shaft, a gear carried by the last named shaft, a driven shaft carrying a gear in mesh with the aforesaid gear, and a lever pivoted to said standard adapted to be moved to engaging position with said propeller for holding the same against rotation.

for engagement with the worm, a worm fixed to the other shaft in engagement with one of the worms upon the first named shaft, a gear carried by the last named shaft, a driven shaft carrying a gear in mesh with the aforesaid gear, and a lever pivoted to said standard and having an upper forked extension adapted to be moved

to inclose the propeller blade to hold the same against rotation.

In testimony whereof I affix my signature in presence of two witnesses.

GEORGE HRIB.
